SHOE INSERT PAD

Vincent R. Casey, Portland, Oreg., assignor to Orral A.
Brown and Mildred D. Brown

Filed Sept. 9, 1971, Ser. No. 179,262

Term of patent 14 years

Int. Cl. D24—04, 99
U.S. Cl. D83—1 J

FIG. 4

FIG. 1

FIG. 3

FIG. 2

FIG. 5

FIG. 1 is a plan view of an insert pad showing my new design;

FIG. 2 is a rear view of the pad;

FIG. 3 is an edge view of the pad;

FIG. 4 is an end view, taken from the upper edge of FIG. 1; and

FIG. 5 is an end view taken from the bottom edge as the parts are shown in FIG. 1.

I claim:

The ornamental design for a shoe insert pad, as shown.
